UNITED STATES PATENT OFFICE.

PAUL AMADEO, OF SHENANDOAH, PENNSYLVANIA.

MAIL-BOX.

1,082,787.

Specification of Letters Patent.

Patented Dec. 30, 1913.

Original application filed August 8, 1912, Serial No. 713,961. Divided and this application filed March 11, 1913. Serial No. 753,503.

To all whom it may concern:

Be it known that I, PAUL AMADEO, a subject of the King of Italy, residing at Shenandoah, in the county of Schuylkill and State of Pennsylvania, have invented certain new and useful Improvements in Mail-Boxes, of which the following is a specification.

My invention relates to improvements in mail boxes, and more particularly to an improved hinged bottom for mail boxes, the object of the invention being to provide a mail box with a bottom consisting of two members movable relative to each other, whereby the bottom is permitted to pivot and direct the mail to one end thereof without any possibility of the mail falling out of the opposite end.

A further object is to provide improved means for holding a pivoted bottom of the character set forth in closed position.

This application is a division of my application for patent filed August 8, 1912, and given Serial No. 713,961.

With these and other objects in view, the invention consists in certain novel features of construction and combinations and arrangements of parts as will be more fully hereinafter described and pointed out in the claims.

In the accompanying drawings: Figure 1 is a fragmentary view in longitudinal section through a mail box illustrating my improved construction of bottom. Fig. 2 is a view in transverse section on the line 2—2 of Fig. 1. Fig. 3 is a fragmentary view in elevation of the inner wall of the mail box illustrating the locking lever. Fig. 4 is a fragmentary view in longitudinal section, and Fig. 5 is a fragmentary bottom plan view of the bottom on a reduced scale.

1 represents the lower portion of a mail box which is provided at its lower end with a bottom 39. The bottom 39 comprises a relatively long member and a relatively short member, the latter I have given separate reference numeral 50, and the longer member is provided at one end with a longitudinal slot in which member 50 telescopes. The relatively long member of the bottom 39 is pivoted between its ends and at both side edges to the walls of the mail box 1, and when the bottom is in closed position, it neatly fits within the lower end of

the box. Cylindrical enlargements 51 are provided on the lower face of the bottom 39 and receive rods 52 integral with member 50, coiled springs 53 being located in said cylindrical enlargements and exert a pressure on the rods, tending to expand the bottom longitudinally and maintaining member 50 always in contact with the wall of the box regardless of the position of the bottom. This is particularly desirable because mail within the box might fall out of the box, and not down the inclined bottom when the latter is in open position, if it were not for this member 50. In other words, the member 50 maintains a closure of the box at this end of the bottom, and to prevent the mail from falling out the sides, I provide triangular plates 47 at the side edges of the bottom which slide against the walls of the box and form the side members of an inclined chute when the bottom is in open position.

To hold the bottom in closed position, I provide a catch 42 which is located in the recess 2 in the wall of box 1, and is pivotally supported between its ends as indicated at 43. A coiled spring 3 holds this catch 42 in normal position, and said catch is adapted to be swung to unlocked position by a suitable key (not shown) which may be inserted through a key hole 45 in the box and engage an arm 44 on the catch. This catch 42 at its lower free end is provided with a beveled lug 5 which is engaged by a beveled lug 4 on the free end of a sprung latch 41. This latch 41 is covered by a casing 46 and is pressed into operative position by a coiled spring 6 as clearly shown in Fig. 1. It is to be understood that the latch 41 will spring into locked engagement with the catch 42 when the bottom is closed, but in order to permit the bottom to open, it is necessary to swing the catch to one side by means of a suitable key as above explained.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention,

what I claim as new and desire to secure by Letters Patent is:

1. The combination with a receptacle, of a bottom pivoted between its ends in said receptacle, said bottom comprising two members overlapping each other, elastic means tending to move the members longitudinally to lengthen the bottom, whereby one end of the bottom is maintained in position against the wall of the receptacle at any incline, substantially as described.
- 10 2. The combination with a receptacle, of a bottom pivoted between its ends in said receptacle, said bottom comprising two

members overlapping each other, one member having cylindrical enlargements thereon, coiled springs in said enlargements, and the other member having rods fixed thereto and movable in the enlargements against the action of the springs, whereby one end of the bottom is maintained in position against the wall of the receptacle at any 20 incline, substantially as described.

In testimony whereof I have signed my name to this specification in the presence of two subscribing witnesses.

PAUL AMADEO.
